(57) **CLAIM**

The ornamental design for an assembled part of a crane having the colors, as shown and described.

DESCRIPTION

The patent or application file contains at least one drawing executed in color. Copies of this patent or patent application publication with color drawing(s) will be provided by the Office upon request and payment of the necessary fee.

1.1 : Side view

2.1 : Side view

A grey connecting part of a jib, a grey counterjib, and an operator's cab with a side plate of the operator's cab which has a lower yellow color field and an upper white color field. The design shown in this figure excludes the shown yellow outer part of the jib connected to the connecting part. 2.1: A grey connecting part of a jib, yellow outer part of the jib connected to the connecting part, a grey counterjib and an operator's cab with a side plate of the operator's cab which has a lower yellow color field and an upper white color field.
